CLAIM

The ornamental design for a toy water cannon, as shown and described.

DESCRIPTION

FIG. 1 is a top, front, left perspective view of a first embodiment of a toy water cannon showing the new design.

FIG. 2 is a bottom, rear, left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top, front, left perspective view thereof shown in an extended position; and

FIG. 10 a bottom, rear, left perspective view thereof shown in the extended position.

FIG. 11 is a top, front, left perspective view of a second embodiment of a toy water cannon showing the new design.

FIG. 12 is a bottom, rear, left perspective view thereof;

FIG. 13 is a front view thereof;

FIG. 14 is a rear view thereof;

FIG. 15 is a right side view thereof;

FIG. 16 is a left side view thereof;

FIG. 17 is a top view thereof;

FIG. 18 is a bottom view thereof;

FIG. 19 is a top, front, left perspective view thereof shown in an extended position; and

FIG. 20 a bottom, rear, left perspective view thereof shown in the extended position.

(Continued)

The dashed lines shown in FIGS. 1-10 illustrate portions of the toy water cannon that form no part of the claimed design.
